Primary Examiner — Katrina A Betton

(57) **CLAIM**

The ornamental design for luggage carriers for vehicles [except for cycles and motorcycles] as shown and described.

DESCRIPTION

FIG. 1.1 is a top view of a luggage carrier for vehicles except for cycles and motorcycles showing my new design; and FIG. 1.2 is a perspective view thereof.

The lines across the reproductions indicate indeterminate length of the product and do not form part of the claimed design.

1 Claim, 2 Drawing Sheets

FIG. 1.1

FIG. 1.2
